UNITED STATES PATENT OFFICE.

MARY M. BROWN, OF ELBERTON, GEORGIA.

ATTACHMENT FOR MUSIC SHEETS.

Application filed May 31, 1921. Serial No. 473,604.

To all whom it may concern:

Be it known that I, MARY M. BROWN, citizen of the United States, residing at Elberton, in the county of Elbert and State of Georgia, have invented certain new and useful Improvements in Attachments for Music Sheets; and I do declare the following to be a full, clear, and exact description of the invention, such as will enable others skilled 10 in the art to which it appertains, to make and use the same.

This invention relates to a novel device intended to be attached to one or more leaves in a music instruction book for beginners, and it has for its principal object to devise a novel way of teaching persons "time" and how to read the notes rapidly and correctly.

Broadly, it is another object of the invention to provide a device of this class which embodies among other details, a horizontally movable indicator which is adapted to be positioned over and successively moved from left to right along the line 25 or staff of the music to indicate the notes that have been read and played and to enable the reader to readily determine the next note to be read.

More specifically, it is a further object 30 of the invention to employ a device of this class embodying the aforesaid horizontally shiftable indicator which is of a width to cover one or more notes, thereby enabling the indicator to function as a shield to 35 cover several of the notes already read and to thus overcome the possibility of permitting the scholar to twice read the same notes.

In addition to the above, it is a further 40 object of the invention to devise novel mounting means for the movable indicator, wherein the mounting means is itself vertically movable to permit it to be positioned over the succeeding lines of music for the purpose of directing the scholar's eyes to 45 the notes on the line over which the mounting means is positioned.

Still another object of the invention is to 50 provide a device of this class which embodies a rigid sectional frame between the sections of which the leaves of the music are clamped; this arrangement permitting the device to serve the additional function of a brace for the leaves to prevent them from drooping when supported on the ledge 55 of the piano or music stand.

Other objects and advantages and fea-

tures of the invention will become apparent during the course of the following description.

In the accompanying drawings forming a 60 part of this specification and in which like numerals are employed to designate like parts throughout the same:

Figure 1 is a front elevational view of the instruction book with the improved attachment in operative position thereon.

Figure 2 is a sectional view taken on the plane of the line 2—2 of Fig. 1.

Figure 3 is a horizontal sectional view taken through the book and track.

Figure 4 is a perspective view of the track member.

Figure 5 is a perspective view of the shield.

Figure 6 is an enlarged detail view of a 75 portion of the front section of the frame.

Referring to the drawings by numerals, 1 designates a frame made up of front and rear sections 2 and 3, hinged or otherwise pivotally connected together, as indicated 80 at 4. It is to be noted that the front section 2 is formed with a relatively large opening 5 through which the notes and lines of music are exposed to enable them to be read and it is understood that the hinged 85 sections of the frames are intended to be clamped over the desired leaf or leaves of an instruction book A as indicated. If desired, the front section may be equipped with a pivotally mounted clip 6 of any suitable construction for retaining the frame sections together and on opposite sides of the page of music.

It has already been intimated that I associate with the frames, a horizontal shiftable indicator, the same being indicated by 95 the numeral 7. While this indicator could be of any construction, it is preferably in the form of a loop which is of considerable width to enable it to have the additional function of serving as a shield to cover a plurality of notes. Any suitable mounting

means may be associated with the indicator. For the purpose of illustration, I have shown a vertically movable track 8 embodying spaced longitudinal bars 9 on which the aforesaid loop or indicator 7 is horizontally slidable. This track is provided at its opposite ends with hooks 10, which are de-

signed to take over the vertical edges of the 100 front section 2 of the frame. In order to 105 prevent the hooks from possibly tearing

the page, against which they slide, and in order to retain their outer faces flush with the rear face of the section 2, the latter may be provided along its vertical edges and 5 in its rear face with vertical channels 11 for reception of the hooks. As before suggested, this construction permits the track and indicator to be positioned over the top staff or line of music and be used downward- 10 ly over the succeeding lines at intervals as the notes are read. It has been before indicated that this is advantageous since it serves to direct the student's eyes to the proper line of music and prevents the same 15 line of notes from being read over again. It may be stated at this point, that any suitable means may be employed to retain the track in the various positions to which it has been moved. In the present instance, it 20 is to be supposed that the hooks on the track engage the front section of the frame sufficiently tight to frictionally retain the track in various positions without employing any special means.

25 The operation of the device is as follows: Assuming that the sections of the frame have been clamped on the desired leaf of music of the instruction book as is shown, and the track and indicator are positioned 30 over the top line of music with the indicator at the extreme left-hand end of the track so as not to interfere with any of the notes, the teacher, by means of a pointer or pencil, will engage the indicator 7 and 35 move it successively along the line of music, covering each note that has been played so that the student will be enabled to determine just what note should be played next. In this way, the student cannot dwell too 40 long on the same note. The device will thus be found helpful in teaching "time" and enabling the student to read at sight with great facility and ease. After all of 45 the notes on the top line have been read, the track 8 is moved down and positioned over the next succeeding line and the operation repeated. It may well be stated at this point that the indicator and shield can be operated by a child's parents if desired, by making use of a metronome. To 50 explain, the metronome will indicate the value of the note and the operator may move the indicator to the next note to be read assisted by the audible sounds of the metronome. The indicator could, of course, be actuated in any other way or by any suitable mechanism.

55 It is clear from the drawings and description that I have evolved and produced 60 a unique device for attachment to one or more of the leaves of a music instruction book for enabling beginners to learn to

read music rapidly and at sight. It is well known that it is quite difficult for beginners, especially children, to concentrate 65 their eyes on the proper note without easily losing the place and there is a great tendency of small children repeating notes which they have already read and played. This disadvantage can be entirely overcome 70 by utilizing a device of this character and moving the indicator in a manner to cover the notes which have been read and to indicate the notes which are to be read. It is also common for music students to encounter much difficulty in rapidly jumping from the right end of the line to the opposite end of the following line. However, by employment of the movable track, a rapid change can soon be acquired, because 75 the notes over which the track is placed are the only ones to be read and played. These and other advantages and features of the invention have doubtless been made apparent from the description when taken in connection with the drawings. Therefore, a more lengthy and detailed description is 80 thought unnecessary.

85 Advantageous and effective results are doubtless insured by the construction and arrangement herein shown. However, the various elements and manner in which they coact with one another may be varied within the scope of the subjoined claims.

90 I claim:

95 1. A device for teaching persons how to 100 read music comprising a frame composed of pair of pivotally connected sections, the front section having an opening of sufficient size to permit the notes to be seen therethrough, a vertically shiftable track extending crosswise of said front section, said track having hooks at its ends slidably engaging the vertical edges of said sections, and an indicator slidably mounted on the 105 track for co-operation with the aforesaid notes.

110 2. The structure defined in claim 1, wherein the inner faces of the vertical side portions of the front section of the frame are formed with grooves in which said hooks are received, said grooves being of a depth to render the surfaces of the hooks flush with said inner faces.

115 3. A device of the class described including a track having an elongated opening through which notes of music may be exposed and having inturned support-engaging hooks at its ends, and a non-transparent flattened sleeve slidable on said track and 120 serving both as a shield and an indicator.

125 In testimony whereof I have hereunto set my hand.

MAMIE M. BROWN.
